UNITED STATES PATENT OFFICE

MARCEL CUEL, OF PARIS, FRANCE, ASSIGNOR TO SOCIETE DU VAPORISATEUR LE FRISON, OF PARIS, FRANCE

ATOMIZER

Application filed April 5, 1927, Serial No. 181,095, and in France June 18, 1926.

This invention relates to atomizers of the manually operable type. The object of the invention is to provide an atomizer having provisions for hermetically closing the receptacle to which it is attached by a simple adjustment and for easily clearing the atomizing tube of foreign matter, whenever it becomes desirable to do so. Other subsidiary objects and advantages of the invention will become apparent hereinafter.

Referring to the accompanying drawings: Fig. 1 is a vertical sectional view through the atomizer;

Fig. 2 is a perspective view of a stopper which forms part of the atomizer;

Fig. 3 is a view similar to Fig. 1, but showing the stopper in a different angular position;

Fig. 4 is a horizontal section through the atomizer showing the stopper in still another position; and

Fig. 5 is a detail view of the stopper seat.

The atomizer comprises a cup 1 formed of metal or other suitable material and adapted to fit over the neck of a bottle or other receptacle in which is contained the supply of liquid to be atomized. The cup 1 has a thickened upper end in which is formed a conical bore the axis of which is offset laterally from the axis of the cup, an opening 3 being formed in the wall of the bore at one side and a passageway 4 opening into the bore at a diametrically opposite point. The passageway 4 opens at its outer end into a bore in which is secured one end of a rubber tube 6, the other end of which is adapted to be secured to a rubber bulb.

A stopper 2 has a nice fit with the bore in cup 1. This stopper is formed with a notch 15 adapted to register with opening 3 or with the passageway 4 and is also formed with a slot 13 opening at the side and bottom of the stopper and extending to about the center axis of the stopper. The recess 15 is connected with the slot 13 by a threaded hole and in this hole is adapted to be screwed the end of an atomizing tube 16, formed with a small aperture 17 in its side near the upper end. The tube 16 is straight before it is assembled 50 with the stopper, being first screwed into the

threaded hole in the stopper and then bent to the position shown in the drawings. The handle of the stopper is formed with a laterally projecting lug 18^a which is adapted to abut shoulders 19^a and 19^b formed at the upper end of the cup shaped member 1. These shoulders permit the stopper to be rotated through an angle of about 270°.

Fig. 1 shows the atomizer in operative position and the operation will be obvious. By operating the bulb not shown, air is pumped through tube 6 and passageway 4 into the receptacle to which the atomizer is applied, forcing the liquid contained therein up through tube 6, where it is broken up and atomized by air entering the restricted opening 17 and issues from the extremity 14' of the tube in a fine spray passing out through the aperture 3 in the member 1. In this position of the parts lug 18^a is engaged with shoulder 19^b. In atomizers of this type it frequently becomes necessary to clear the atomizer tube 16 of foreign matter, and it is one of the main objects of the present invention to render this clearing operation effective and easy to carry out. According to the present invention clearing of the tube 16 is effected by rotating the stopper 2 from the operative position shown in Fig. 1 to the position shown in Fig. 3. In this position the recess 15 in the stopper and the opening of tube 14 registers with passageway 4, and the tube 16 can be effectively cleared of foreign matter by operating the bulb and forcing air through the tube 6, passageway 4 and tube 16. This current of air will force out any foreign matter in the tube, and the air thus pumped through the tube will escape through the opening 17 and the bottom of the tube and to the outside of the receptacle through slot 13 and opening 3. The tube 16 can thus be easily cleared at will without disassembling the parts. When the stopper has been turned to the position shown in Fig. 4, which is about 270° from the position shown in Fig. 1, lug 18^a engages shoulder 19^a, this being the position of the stopper when the atomizer is not in use. It will be observed that in this position, the stopper hermetically shuts off communication with the interior of

the tube either through passageway 4 or through aperture 3, thus effectively preventing evaporation of the liquid in the receptacle.

5. What I claim is:

An atomizer comprising in combination, an inverted cup shaped member adapted to fit the neck of a bottle or container and having a relatively thick end in which is formed a vertical bore, said end having two diametrically opposite lateral openings, a rubber tube for compressed air communicating with one of said openings, a stopper rotatably mounted in said bore and having a slot opening at the bottom and side adapted to register with said opening and having a recess registering with the other opening and having a substantially horizontal aperture between said slot and recess and an atomizing tube secured in said aperture with its end projecting into said recess and formed with a restricted opening, said tube being bent so as to extend substantially vertically through said slot.

25. In testimony whereof I hereunto affix my signature.

MARCEL CUEL.
